UNITED STATES PATENT OFFICE.

EMIL HOFFMANN, OF COLOGNE, GERMANY.

TOOL FOR THE CONNECTION OF METAL STRIPS AND THE LIKE.

Application filed September 24, 1920. Serial No. 412,625.

(GRANTED UNDER THE PROVISIONS OF THE ACT OF MARCH 3, 1921, 41 STAT. L., 1313.)

To all whom it may concern:

Be it known that I, EMIL HOFFMANN, a citizen of the German State, residing at Cologne, Marienburg Lindenallee 62, in the 5 State of Germany, have invented certain new and useful Improvements in Tools for the Connection of Metal Strips and the like (for which I have filed applications in Germany, March 29th, 1916, Patent Number 10 297,521; Austria, July 3rd, 1916, Patent Number 75,880; Switzerland, July 3rd, 1916, Patent Number 74,043; Netherland, July 15 8th, 1916, Patent Number 3,231; Hungary, July 28th, 1916, Patent Number 71,533; Denmark, March 11th, 1918, Patent Number 23,911; Sweden, March 13th, 1918, Patent Number 45,602; Norway, March 14th, 1918, Patent Number 29,184; Czechien, September 29th, 1919; Belgium, October 21, 20 1919; Luxemburg, October 1st, 1919, Patent Number 11,524; France, October 21, 1919; Great Britain, April 25th, 1920; Poland, April 26th, 1920), of which the following is a specification.

25 It is known to connect metal-strips for tying of packages or parcels and overlapping pieces of sheet-metal by punching tongues from the strips or pieces, said tongues being adapted to clamp and hold 30 said strips or pieces together. This method of joining allows to dispense with rivets, special clamps and the like.

The present invention relates to a new and useful improvement in a tool for the 35 execution of this known method of connection. This tool is constructed of two members in such a manner, as to secure a tight connection of the strips or pieces by two closing movements of the tool-members 40 (tongs).

The drawing shows:

Fig. 1 the opened tool-members or tongs in side-elevation,

Fig. 2 the closed tool-members or tongs 45 in side-elevation and partly in a longitudinal section of the tongs mouth as well as two crossed strips after performing the joint,

Fig. 3 a plan view of the tongs of Fig. 2,

50 Fig. 4 a plan view of two crossed and joined strips,

Fig. 5 a plan view of two longitudinally joined strips.

In the upper elongated part *a* of the tongs-mouth is pivotally arranged on a pin *d* a 55 well-known punching-die *c* having two points *c*¹ which enter a slot of the lower part *b* at the closing movement of the tongs-mouth. Within the tongs-mouth there is fixed on the part *b* a permanent or adjustable guide- or stop-piece *b*² for the strips *f* to be joined, the upper part *b*¹ of said guide- or stop-piece being provided with a guide-slot for the punching-die *c*.

With the tongs it is possible to join crossed 65 (Fig. 4) or longitudinally (Fig. 5) superposed strips as well as superposed pieces of sheet-metal. For this purpose the strips are laid into the tongs-mouth in the manner as shown in Figs. 2 and 3 by moving the opened 70 jaws of the tongs-mouth sideways so as to grip the strips. When the strip or strips lying parallel to the tool-members are in contact with the guide-piece *b*² (Fig. 3) the jaws are closed and the tongs *c*¹ of the 75 punching-die *c* are forcing two tongues *g* (Fig. 2) out of the strips which tongues have an outwardly curved form and are pressed against the strips with the front part *a*¹ of the tongs-mouth by a second movement of the jaws, attaining thereby the tight connection without rivets, clamps or the like.

In Figs. 4 and 5 *g*¹ are the openings left by the forced out tongues. With the cross-connection (Fig. 4) the two tongues are forced out at such distance that the crossing strip *f*¹ becomes partly cut out on both sides. These cuttings serve to avoid a longitudinal displacement of the strip *f*¹ by 85 the interlocking of the tongues *g* into the 90 said cuttings after the performance of the joint.

I claim:

1. A tool for uniting metal strips, comprising opposed pivoted jaw members, a 95 punching die movably mounted in one jaw member, a guide carried by the other jaw member for guiding the punching die and metal strips to be united, whereby in the 100 movement of the jaws together the die will be operated to unite the strips.

2. A tool for uniting metal strips, comprising a pair of pivotally connected jaw members, a punching die pivotally mounted 105 in one jaw member for punching tongues in

metal strips, a guide carried by the other jaw member for guiding the punching die and the metal strips to be united, and means on one of the jaw members adapted to cooperate with the other jaw member for flattening and uniting the tongues punched by the punching die.

3. A tool for uniting metal strips, comprising a pair of pivotally connected jaw members, a punching die carried by one of said members, means for guiding the punching die, means carried by one of the jaws for guiding metal strips to be united, and an element carried by one of the jaws for cooperation with the other jaw, whereby the punching die will punch tongues in the metal strips and the said element will flat-

ten and unite said tongues in its cooperative relation with the jaw.

4. A tool for uniting metal strips, comprising a pair of pivotally connected jaw members, a die member pivotally mounted in one jaw member having a pair of points formed on the end thereof adapted to punch oppositely formed tongues and metal strips in the operation thereof, and a guide member for the punching die and the metal strips, one of said jaw members being formed with a lateral projection for cooperation with the other jaw adapted to unite the tongues punched from the metal strips in the movement of the jaws.

In testimony whereof I affix my signature.
EMIL HOFFMANN.
